UNITED STATES PATENT OFFICE.

WILLIAM OPPENHEIMER, OF LONDON, ENGLAND.

CAPSULE.

SPECIFICATION forming part of Letters Patent No. 462,990, dated November 10, 1891.

Application filed September 23, 1891. Serial No. 398,711. (No specimens.) Patented in England January 29, 1891, No. 1,651.

To all whom it may concern:

Be it known that I, WILLIAM OPPENHEIMER, manufacturing chemist, a subject of the Queen of Great Britain, residing at 1 and 3 Sun Street and 39 Wilson Street, Finsbury Square, London, England, have invented a certain new and useful Improvement in Capsules and in the preparation of the same for use, (for which I have applied for a patent in Great Britain, No. 1,651, bearing date January 29, 1891,) of which the following is a specification.

My invention relates to those forms of medicine which are conveyed into the system intact and are only intended to dissolve and intermix after being taken into the stomach or elsewhere, where they are intended to operate; and the object of my invention is to improve and extend the use of such preparations by manufacturing them in the form of capsules, each having a partition dividing it into a series of chambers which contain the different kinds of medicine.

The invention is illustrated by the accompanying drawings, in which—

Figure 1 is a transverse sectional view of a capsule embodying my invention. Figs. 2 to 20, inclusive, are similar views showing variations in the shape of the capsule.

In carrying out my invention I make up the compound medicines as capsules, wafers, pills, or granules 1, of any convenient form, such as the lentil or double-convex lens or 35 globular, semi-globular, double globular, or of any other preferred shape.

The capsules are each composed of a soluble casing or shell, which is integral with a soluble partition or partitions 3, formed of the same material as the shell or casing, for 40 the purpose of dividing the soluble casing into a series of chambers 2, adapted to contain different kinds of medicine. The medicines are preserved entirely separate from each other by the soluble partition or partitions 3, formed integral with the soluble casing, as before explained, and the casing and partition or partitions dissolve when taken internally for the purpose of liberating the medicines. The inclosed medicine may be 45 50 55 best suited to the required treatment.

The medicines so prepared as herein described may, if preferred, be dissolved or mixed in water or other suitable fluid or matter and taken as a draft.

I claim—

A capsule consisting of a soluble shell or casing formed integral with a soluble partition to provide separated chambers for different kinds of medicine, said shell or casing and partition dissolving when taken internally for the purpose of liberating the medicines, substantially as described.

Dated this 16th day of June, 1891.

WILLIAM OPPENHEIMER.
